UNITED STATES PATENT OFFICE.

FRANK JANOUSHEK, JR., OF MILWAUKEE, WISCONSIN.

DEVICE FOR FACILITATING THE BRONZING OF PRINTED MATTER.

No. 818,091.

Specification of Letters Patent.

Patented April 17, 1906.

Application filed August 3, 1905. Serial No. 272,482.

To all whom it may concern:

Be it known that I, FRANK JANOUSHEK, Jr., residing in Milwaukee, in the county of Milwaukee and State of Wisconsin, have invented new and useful Improvements in Devices for Facilitating the Bronzing of Printed Matter, of which the following is a description, reference being had to the accompanying drawings, which are a part of this specification.

My invention has relation to improvements in devices for facilitating the bronzing of printed matter.

Under the ordinary method of applying gold and other bronzes to freshly - printed matter a piece of raw cotton is dipped into the powdered bronze, and the bronze in this manner is applied to the printing. A method of this character is open to considerable objection, inasmuch as in carrying out the same the light bronze - powder will necessarily fly around the room and settle indiscriminately upon different objects, which is not only detrimental to such objects, but, furthermore, results in considerable waste of powder.

It is the primary object of my invention to provide a device wherein in the operation of bronzing the disadvantages above referred to are entirely obviated.

With the above primary object in view the invention consists of the devices and parts or the equivalents thereof as hereinafter set forth.

In the accompanying drawings, Figure 1 is a plan view of the invention, a part being broken away and showing the flexible sleeves as extended outwardly ready for the insertion of the arms therein. Fig. 2 is a side view of Fig. 1. Fig. 3 is a central longitudinal sectional view on the line 3 3 of Fig. 1, and Fig. 4 is a vertical transverse sectional view on the line 4 4 of Fig. 1.

Referring to the drawings, the numeral 5 indicates a casing which is preferably sustained at a convenient distance above the floor by means of legs 6. The top of this casing is provided with a large opening 7, which opening is covered by means of a plate 8 of some suitable transparent material, such as glass, the edges of said plate being set in grooves formed in the bordering edges of said top opening. Within the casing and at a desired distance above the bottom of said casing is a horizontal partition 9, forming a table,

upon which the printed matter to be bronzed is laid.

Below the partition and near the front side of the casing and extending across the casing is a long drawer 10, which is preferably subdivided, by means of a central partition, into two compartments 11 and 12. This drawer is adapted to be withdrawn from the casing through an opening 13 in one side of said casing, the drawer being provided with a handle for convenience in withdrawing the same. The horizontal partition above the two compartments of the drawer 10 is provided with two openings, one of said openings, 14, being above the compartment 11 of the drawer, and the other of said openings, 15, being above the compartment 12 of the drawer. These openings are normally closed, respectively, by means of removable covers 16 and 17. Also beneath the partition 9 and toward the rear side of the casing is a drawer 18, which is adapted to be withdrawn rearwardly through an opening 19 in the rear side of the casing. The partition 9 above the drawer 18 is provided with an opening 20, which is normally closed by means of a removable cover 21.

The sides of the casing are provided with long openings 22 and 23, respectively, which are preferably in line with each other and communicate with the space of the casing above the partition 9. These openings are normally closed by means of downwardly - swinging hinged doors 24 and 25, respectively. Each door is releasably held in closed position by means of a catch 26, turned up to engage against the inside of the side piece of the casing, the said catch being rigidly mounted on the inner end of a short spindle 27 extending through the door, the said spindle being provided on its outer end with a handle on a knob 28 for convenience in turning it.

Secured to one side of the casing and projecting outwardly therefrom is a dome-shaped receptacle 29, which is provided with an open inner side communicating with an opening 30 in the side of the receptacle, said opening leading to the space of the receptacle which is above the partition 9.

The sides of the casing toward the front are preferably on an incline and converge toward the front wall of said casing. In each of these converged portions are openings 31 31, which communicate with the front

portion of the space above the partition 9. The inner ends of flexible sleeves 32 are secured to the bordering edges of these openings 31, and said sleeves when the device is 5 not in use are extended outwardly, as clearly shown in the drawings. The outer ends of the sleeves are advisably drawn to a closed position by means of encircling elastics 33 33.

The top of the casing, in which is provided 10 the glass-covered opening 8, is preferably in the form of a hinged cover 34, the hinges being at the rear thereof. When this hinged cover is turned downwardly to closed position, it may be detachably locked by means 15 of a locking mechanism 35. By thus providing for the top being opened convenient access may be obtained to the interior of the casing for the purpose of cleaning.

The two compartments 11 and 12 may be 20 conveniently used for the purpose of containing raw cotton and a supply of bronze-powder, the raw cotton being placed, say, in the compartment 11 and the bronze-powder in the compartment 12.

25 In the use of the device one of the doors 24 is unlocked and allowed to swing downwardly on its hinges. The printed matter to be bronzed is then pushed through the opening controlled by this door and is sup-

30 ported on the partition 9. A certain amount of the bronze-powder is taken from its compartment of the drawer 10 and placed in the receptacle 29, being thereby in convenient position for use. The operator then inserts 35 his arms into the sleeves 32 and forces his arms through the openings 31 and into the space above the partition 9 of the casing, the sleeves being thereby turned wrong side out and the elastics 33 drawing the sleeves tightly

40 around the wrists of the operator. The operator then takes a required amount of the raw cotton from one of the compartments of the drawer 10 and dips said raw cotton into the bronze-powder contained in the receptacle 29. The bronze-powder is then applied to the printed matter lying on the partition 9 by rubbing the raw cotton over said 45 printed matter. It will be seen that the entire operation is thus performed within a closed casing with absolutely no chance for the light powder to escape, inasmuch as even

50 the openings 31, through which the arms are inserted, do not offer a means for the escape of the powder on account of the fact that the sleeves which are drawn around the wrists of the operator prevent the escape of any powder through these openings. It will also be evident that the operator is afforded means for viewing the work as it progresses through

55 the transparent top 8 of the casing. When the bronzing operation is completed, the printed matter, with the bronze applied thereto, can either be passed out of the casing through one of the openings 22 or 23 or may 60 be deposited in the drawer 18.

While two of the openings 31 and two sleeves 32, extending from said openings, are desirable, inasmuch as they enable the operator to insert both arms into the casing for the purpose of effecting the bronzing operation, 70 yet I do not wish to be understood as specifically limiting myself thereto, inasmuch as only one of said openings and a single sleeve extending therefrom could be employed without departing from the spirit and scope 75 of my invention and satisfactory results secured, although, as stated, the construction shown is the more desirable one. In fact, I would consider the omission altogether of the flexible sleeves and the provision of either 80 one or two of the openings 31 as within the spirit and scope of my invention; but in such case some of the powdered bronze would not only be afforded an opportunity to escape through the opening or openings, but would 85 also settle on the arm or arms of the operator.

I also wish it understood that other details of construction can be omitted or changed without departing from the spirit and scope of my invention—as, for instance, 90 the provision of the drawers, the receptacle 29, the glass-covered top opening, and the side openings 22 and 23 are not absolutely essential.

What I claim as my invention is—

95 1. In a device for facilitating the bronzing of printed matter, the combination with a casing having an opening for the insertion of the arm of the operator, and the interior space of said casing provided with a table for supporting the printed matter to be bronzed, of a receptacle for the bronze extending laterally outwardly from the casing, and having an open inner side communicating with an opening through the side of the casing. 100

105 2. In a device for facilitating the bronzing of printed matter, the combination of a casing having an opening for the insertion of the arm of the operator, and subdivided internally by a horizontal partition, said partition forming a table for supporting the printed matter to be bronzed, a drawer beneath the partition, the said partition provided with an opening communicating with the drawer, and a flexible sleeve extending from 110 the arm-opening of the casing.

115 3. In a device for facilitating the bronzing of printed matter, the combination of a casing having an opening for the insertion of the arm of the operator, and subdivided internally by a horizontal partition, said partition forming a table for supporting the printed matter to be bronzed, a drawer beneath the partition, said partition provided with an opening leading to the drawer, and a receptacle for the bronze projecting outwardly laterally from a side of the casing, and having an open inner side communicating with an opening in said side of the casing. 120

125 4. In a device for facilitating the bronzing 130

of printed matter, the combination of a casing having an opening for the insertion of the arm of the operator, and said casing subdivided interiorly by a horizontal partition, the 5 partition forming a table for supporting the printed matter to be bronzed, a drawer beneath the partition, with means for gaining access through the partition to the drawer, a receptacle for the bronze projecting outwardly 10 laterally from a side of the casing, and having an open inner side communicating with an opening in said side of the casing, and a flexible sleeve secured in the arm-opening of the casing and extending therefrom. 15 5. In a device for facilitating the bronzing of printed matter, the combination of a casing having an opening in its top covered with a transparent material, and said casing also

having an opening for the insertion of the arm of the operator, and divided interiorly 20 by a horizontal partition, said partition forming a table for supporting the printed matter to be bronzed, a drawer beneath the partition, with means for gaining access through the partition to the drawer, and a receptacle 25 for the bronze projecting outwardly laterally from a side of the casing, and having an open inner side communicating with an opening in said side of the casing.

In testimony whereof I affix my signature 30 in presence of two witnesses.
